UNITED STATES PATENT OFFICE.

CLARENCE E. WILLIAMS, OF CHICAGO, ILLINOIS, ASSIGNOR TO THE BEAVER PRODUCTS CO., INC., OF BUFFALO, NEW YORK, A CORPORATION OF NEW YORK.

PLASTER BOARD.

Application filed August 18, 1922. Serial No. 582,605.

To all whom it may concern:

Be it known that I, CLARENCE E. WILLIAMS, a citizen of the United States, and a resident of the city of Chicago, county of Cook, State of Illinois, have invented an Improvement in Plaster Board, of which the following is a specification.

This invention relates to composite building board, such as plaster board or the like, and to the method of making it.

Among other objects, the invention is intended to provide a plaster board having an improved protected edge which shall be of neat appearance, secure and durable.

The invention consists in the novel constructions, combinations and methods, hereinafter described or claimed, for carrying out the above stated objects and such other objects as will hereinafter appear.

The invention may be more readily understood by reference to one illustrative method and construction embodying the invention and shown in the accompanying drawing.

In said drawing:

Fig. 1 illustrates a perspective view of a portion of a plaster board having a protected edge embodying this invention.

Fig. 2 is a cross section transversely of the board, illustrating the same at one stage of manufacture before the margins of the cover sheets have been folded over the edges of the plaster body.

Fig. 3 is a cross section of the board along the lines 3—3 of Fig. 1 showing the illustrative protected edge in finished form.

The invention is illustrated as applied to a double-face plaster board, that is, a board either side of which may be employed as the face side of the board. In the drawing 10 and 11 designate cover sheets which may be termed, for convenience, top and bottom cover sheets, respectively. Such cover sheets are preferably of fibrous material of the

proper weight and quality, such as paper. Between the cover sheets is a body 12 of plaster or the like to which the cover sheets preferably adhere from edge to edge of the plaster body. This adhesion of the cover sheets to the plaster body reinforces the board and makes the same much stronger than the body of plaster alone.

The cover sheets 10 and 11 are preferably of equal width and are sufficiently wider than the intended width of the board to provide margins 13 and 14 which, when folded, cover wholly or partly the edges 15 of the plaster body. These margins preferably cover the edges 15 (these edges being the side edges of the board) without overlapping. In the illustrative form, the joint or space 16 between the margins falls approximately at the middle of the edge of the board. The margins are cemented in place preferably by the adhesive character of the 65 plaster itself.

To improve the adhesion of the folded margins to the plaster body and to render the same less likely to unfold, these margins are treated in a suitable manner to render 70 them more pliable and less likely to unfold and pull loose from the plaster. Heretofore the inherent stiffness and resilience of the paper cover sheets, particularly when the edges of the cover sheets fall at the edges 75 of the board, has caused the folded margins to pull loose from the plaster before the same had been firmly cemented in place by the setting of the plaster. In the form illustrated the margins 13 and 14 are thinned, 80 scarfed or beveled, as at 17, thus weakening the margins and rendering them more pliable. Preferably, this scarfing or beveling commences at a point 18 somewhat back of the intended corner of the board. The 85 margins so beveled fold more easily at the corners of the board and adhere more readily to the plaster body. Heretofore at the corners of the board the stiffness of the paper has tended to cause the same to pull 90 away from the plaster during the initial stages of manufacture, while the plaster was in plastic condition. When the margins have been weakened, they conform more readily to the body of plaster and adhere 95 thereto until the same has set.

The beveling or feathering of the margins 14 and 15 somewhat mutilates the same or at least exposes or loosens the fibres of the paper so that the same may become more 100 intimately bonded with the body of plaster. The margins may be beveled to any degree thought necessary to produce the desired effect, namely to cause the margins to re-

main in folded relation in contact with the plaster until the same has set sufficiently.

The margins of the cover sheets need not necessarily be scored along the corners of the board to cause the same to fold readily.

5 The scarfing of these margins back of the corners of the board obviates this.

Plaster board of this character may be manufactured in any suitable manner. If 10 what is termed as the continuous process be employed, plaster is placed in suitable quantities upon a traveling cover sheet, called the bottom sheet. In the illustrative form the sheet 11 is employed as the bot-

15 tom sheet. The top cover sheet 10 is then applied and, preferably simultaneously, the plaster is spread to an even depth across the board. At some stage in the manufacture of the board, the margins 13 and 14 are 20 folded over the edge of the plaster body. In the preferred method the lower margins 14 are folded up into position before the top cover sheet is applied and before the plaster is spread to an even depth over the 25 bottom sheet. After the top sheet has been applied and the board has assumed shape, the top margins 13 are folded over the edges of the plaster body. Suitable means are provided for confining the plaster to the 30 proper width and to prevent the same from flowing beyond the margins.

At some stage in the manufacture of the board, preferably at a suitable distance from the application of the plaster, the 35 margins 13 and 14 are scarfed or beveled. This may be accomplished by rapidly rotating emery wheels or other grinding devices, the surfaces of which are set at the proper angle to the surface of the sheet to produce 40 the desired result. In the illustrative form this bevel is produced on the inner surfaces of the margins. This preserves the surface finish of the outer surface of the margins. However, if desired, the bevel may occur 45 on the outer surface of the margins.

Pressure is applied to the edges of the board while the plaster is still in plastic condition to cement the folded margins firmly in place, and to produce a mechanical 50 bond between the plaster and the loosened fibres on the beveled margins and with whatever mutilation of the margins may be present as a result of the scarfing operation. This pressure may be removed when the 55 plaster, with the cooperation of the cover sheets, is sufficiently set to retain its proper shape, particularly at the edges.

Obviously, the construction, conformation 60 or shape of the edges of the board may be varied considerably according to requirements. For example, one or both faces of the board may be beveled near the edges to provide an enlarged area for receiving 65 plaster intended to cover the joints of the adjacent boards when the same are placed

in a wall. Furthermore, the edges of the board need not be plane surfaced and at right angles to the faces of the board, but may be concave or formed to any other desirable contour.

Obviously, the invention is not limited to any particular construction and the details of the illustrative board and method of making it may be variously modified. Moreover, it is not indispensable that all 75 features of the invention be used conjointly, as certain features may be employed to advantage in various different combinations and sub-combinations.

Having thus described my invention, I 80 claim:

1. A plaster board comprising, in combination, a body of plaster or the like, covering sheets disposed over the respective faces of said body, the margins of said cover 85 sheets being folded over the edges of said body in non-overlapping relation, and certain of said margins being weakened to reduce the stiffness of the material thereof.

2. A plaster board comprising, in combination, a body of plaster or the like, cover sheets covering the opposite faces of said body and adhering thereto to reinforce said body from edge to edge, the margins of said cover sheets being folded over and cemented to the edges of said body without overlapping, certain of said margins being 95 reduced in thickness.

3. A plaster board comprising, in combination, a body of plaster or the like, cover 100 sheets covering the opposite faces of said body and adhering thereto to reinforce said body from edge to edge, the margins of said cover sheets being folded over and cemented to the edges of said body without overlapping, certain of said margins being reduced in thickness for a distance beyond 105 the corners of said body.

4. A plaster board comprising, in combination, a body of plaster or the like, cover 11 sheets covering the opposite faces of said body and adhering thereto to reinforce said body from edge to edge, the margins of said cover sheets being folded over and cemented to the edges of said body without overlapping, certain of said margins being 115 tapered whereby the same remain more readily in folded relation.

5. A plaster board comprising, in combination, a body of plaster or the like, cover 12 sheets covering the opposite faces of said body and adhering thereto to reinforce said body from edge to edge, the margins of each of said cover sheets being tapered, and folded over the edges of said body and cemented 13 thereto.

6. A plaster board comprising, in combination, a body of plaster or the like, cover 14 sheets covering the opposite faces of said body and adhering thereto to reinforce said 15

- body from edge to edge, the margins of each of said cover sheets being tapered and folded over the edges of said body and cemented thereto without overlapping. 40
7. A plaster board comprising, in combination, a body of plaster or the like, cover sheets covering the opposite faces of said body and adhering thereto to reinforce said body from edge to edge, the margins of 45
- 10 each of said cover sheets being tapered for a distance back of the corners of said body and folded over the edges thereof and cemented thereto. 50
8. A plaster board comprising, in combination, a body of plaster or the like, cover sheets disposed over the respective faces of said body and having margins thereof reduced in thickness for a distance back of the corners of said body to render said margins more pliable, said margins being folded over to cover the edges of said body, and cemented thereto. 55
9. A plaster board comprising, in combination, a body of plaster or the like, cover sheets disposed over the respective faces of said body and having margins thereof reduced in thickness for a distance back of the corners of said body to render said margins more pliable, said margins being folded over 60
- 25 to cover the edges of said body, to meet substantially along the middle thereof without overlapping, and being cemented thereto. 65
10. The method of making plaster board which comprises applying cover sheets to 70
- 30 the opposite faces of a body of plaster or the like, treating said cover sheet margins to render them more pliable, folding the same over the edge of said body without overlapping and cementing the same thereto. 75
11. The method of making plaster board which comprises applying cover sheets to the opposite faces of a body of plaster or the like, reducing the thickness of said cover sheet margins to render the same more pliable, folding said margins to cover the edges of said body and cementing the same thereto. 80
12. The method of making plaster board which comprises applying cover sheets to the opposite faces of a body of plaster or the like, reducing the thickness of said cover sheet margins from a point beyond the corners of the edge of said body to render the same more pliable, folding said margins to cover the edges of said body and cementing the same thereto. 85
13. The method of making plaster board which comprises applying cover sheets to the opposite faces of a body of plaster or the like, tapering said cover sheet margins to render the same more pliable, folding said margins to cover the edges of said body without overlapping and cementing the same thereto. 90
14. The method of making plaster board which comprises applying cover sheets to the opposite faces of a body of plaster or the like, grinding the margins of said cover sheets so as to render the same more pliable, folding said margins to cover the edges of said body without overlapping and cementing the same thereto. 95

In testimony whereof, I have signed my name to this specification.

CLARENCE E. WILLIAMS.
